UNITED STATES PATENT OFFICE.

BENJAMIN O. FANSLOW, OF NEW YORK, N. Y., ASSIGNOR TO NEW ERA MFG. CO., OF NEW YORK, N. Y., A CORPORATION OF NEW YORK.

CHECK-PROTECTOR.

1,260,170.

Specification of Letters Patent.

Patented Mar. 19, 1918.

Application filed June 26, 1912. Serial No. 706,343.

To all whom it may concern:

Be it known that I, BENJAMIN O. FANSLOW, a citizen of the United States, residing in the borough of Manhattan, city, county, and State of New York, have invented a new and useful Improvement in Check-Protectors, of which the following is a description.

This invention relates to check-protectors, and has particular reference to apparatus for simultaneously marking and printing checks, notes and other similar instruments, in such manner as to prevent any possibility of changing or "raising" the same without detection or destroying the value thereof as a negotiable instrument.

Among the objects of my invention may be noted the following: to provide a simple, cheap and compact structure by means of which the amount of the check can be printed in numerals and simultaneously punched or scored so that the check cannot be altered; to provide an apparatus for simultaneously printing and punching a check or other instrument and automatically feeding the same; to provide an apparatus for printing, punching and feeding the article and simultaneously inking successive printing and punching surfaces; to provide a hand-operated device for preparing a check or other similar instrument so that it may not be altered, "raised," or otherwise tampered with; and to provide means whereby checks and other instruments may have imposed upon the surface thereof, in any position desired, one or more figures or numerals of predetermined character.

With the above objects in view, and others which will be detailed during the course of this description, my invention consists in the parts, features, elements and combinations of elements, features and mechanisms, all as hereinafter described and claimed.

In order that my invention may be clearly understood, I have provided drawings wherein:

Figure 1 is a front elevation of a device embodying my invention;

Fig. 2 is a side elevation;

Fig. 3 is a top plan view;

Fig. 4 is a front elevation with the front plates removed;

Fig. 5 is a sectional elevation of the rear of the machine with the supporting-frame removed;

Fig. 6 is a view similar to Fig. 5, showing the parts in another position;

Fig. 7 is a horizontal section taken just below the top of the frame;

Fig. 8 is a section taken on the line 8—8 60 of Fig. 5;

Fig. 9 is a perspective view of the supporting-frame;

Fig. 10 is a detail bottom plan of the guiding-foot; 65

Fig. 11 is a detail of the driving-device for the feeding mechanism;

Fig. 12 is a sectional view showing the co-operative relation of the printing and punching mechanism; 70

Fig. 13 is a detail view showing the means for compelling the uniform action of the die-wheel;

Figs. 14 and 15 show the development of the printing and punching surfaces of two 75 different forms of die-wheels;

Fig. 16 is a perspective view of the presser or stripper, its support being broken away; and

Fig. 17 is an enlarged detail perspective 80 showing the means for raising the spring toe independently of the presser-foot.

Referring to the drawings, Fig. 9, the supporting-portion of the frame consists of a plate having the bottom 1 and integral 85 vertical portion 2 extending to the top of the machine, the bottom being provided at its four corners with the rounded feet 3, which may be of any sound-absorbing material. The bottom is also provided on its 90 upper surface with a transverse groove 4, in which is set a die-plate 5, having on its surface a plurality of diagonal, parallel cutting-edges 6, formed by grooving the surface of the plate obliquely with reference to 95 its surface plane. The groove 4 is more extensive than the plate 5, in order that the latter may be adjusted by means of a screw 7, extending through a slot 8, in the bottom portion 1 of the frame, and having its head slightly countersunk in the bottom surface of the bottom portion of the frame, as clearly shown in Fig. 8. Thus the die or cutting-plate may be adjusted with reference to co-operating knives or die-projections on the 105 rotary die-wheel presently to be described. The bottom portion 1 of the frame is also provided with a depression 10, extending parallel with the groove 4, said depression having longitudinal, narrow extensions 11, for 110

receiving the journals 12 of the anti-friction idle-roll 13, which facilitates the feed of the material through the machine by co-operating with the feeding-rolls. The frame-portion 2 is secured at its upper end to the back edge of the top portion 14 of a U-shaped frame-part having depending portions which form the side-walls 15, extending to near the upper surface of the bottom portion 1. The back edges of the side-walls 15 are cut away from the point 16, to the lower ends thereof, and, at the latter, are rounded as at 17, to correspond with the shape of the bottom portion of the frame at its juncture 15 with the back-portion 2, the slot thus formed between the back-portion 2 and the walls 15 being extended to the front of the machine between the lower ends of the walls 15 and the upper surface of the bottom-portion 20, thus providing an L-shaped slot 18, for receiving the check, etc., to be operated upon. Working in the slot 18 is a gage-bar 19, the same extending from side to side of the machine and being provided at its outer ends, which extend beyond the frame, with the knurled finger-pieces 20, the said bar 19 being also provided at the inner ends of the knurled portions with frictional enlargements 21, which co-operate, respectively, at opposite ends of the bar, with walls 15 and the edge of the back-portion 2 of the frame. The bottom-portion 1 extends a short distance in front of the face of the machine, thus producing a ledge upon which the check may be set preparatory to entering the same through the guide-slot 18, into engagement with the gage-bar 19. The face of the machine is closed by the lower dial-plate 22, secured at its four corners by means of screws 23 to the front edges of the depending-walls 15, and is provided on its face with the several figures and characters 24. The dial-plate 22 is provided at its lower edge with a semi-circular, cut-out portion 25, for the purpose of exposing the die-wheel when it is depressed into engagement with the die-plate 5. Centrally, above the cut-out portion 25, the dial-plate is provided with an elongated slot 26, through which extends the shaft of the die-wheel, upon the outer end of which is secured the pointer 27, by means of the thumb-screw 28. The slot 26 permits the shaft and pointer to reciprocate relatively to the dial-plate 22. The upper portion of the face of the machine is closed by the face-plate 29, which conforms in shape to the remaining portion of the frame, being secured thereto at its lower corners by means of the screws 30 and to the portion 14 of the frame by means of the screw 31. As shown in Figs. 2 and 8, the plates 22 and 29 are beveled inwardly correspondingly as at 32, so as to make a dust-tight juncture and neat closure.

65 The handle 33 incloses a cap-tube 34, the lower end of which is flanged at 35, which in turn incloses a tubular spindle 36, extending vertically from the top-portion 14 of the frame. A washer 37 surrounds the spindle 36 and rests upon the frame-portion 14, thus co-operating with the flange 35, of the cap 34, to deaden the sound and absorb the shock, said washer being made of soft or elastic material, such as leather, rubber, etc. A plunger 38 extends through the frame-portion 14 and at its upper end is provided with screw-threads 39, providing means for firmly securing the handle 33 thereto, the screw-threaded portion extending into a correspondingly screw-threaded bore extending 75 above the head of the cap 34. A washer 40 surrounds the plunger 38, within the cap 34, and has resting against it the upper end of a coil-spring 41, surrounding the plunger and having its lower end engaging the solid 80 portion of the top of the frame 14 within the spindle 36. Thus, the plunger is normally held elevated and under tension to hold the mechanism of the apparatus normally in elevated position within the frame. 85 The plunger 38 is provided at its lower end with a head 42, extending transversely thereof, said plunger being swiveled to the head so as to have rotation relatively thereto, and said head having its extreme opposite ends 90 guided in grooves 43, in the opposite depending-portions 15 of the frame, the grooves thus holding the head from lateral movement and guiding said head and the mechanism carried thereby within the frame. 95 The head 42 has the shaft 43 journaled therein and extending therethrough and through the dial-plate 22 of the machine, to the forward end of which journal the pointer 27 is secured by means of the thumb-screw 28. Just inside the dial-plate, the die-wheel 44 is secured to the shaft 43 in any suitable manner, so as to move with the latter and receive rotation, as presently described. The die-wheel is held from forward movement on the shaft by the spanner-nut 44. The die-wheel 44 is provided circumferentially with a plurality of elevated portions forming die-projections 45, between which are the depressions 46, each of the 100 projections 45 being provided with transverse knives 47, formed by grooving the surface of said raised portions diagonally in parallel lines, as at 48, this formation of the 105 surface of the elevated portions being made 110 to correspond with the formation of the surface of the die-plate 5. By thus forming the die-plate and die-wheel, the co-operating portions of the said two parts are provided with parallel, diagonally-arranged cutters, 115 the edges of which are formed at the vertex of an acute-angle; that is to say, one wall of each groove is vertical, while the other is arranged at an acute-angle thereto, and the cutting edges of one member being arranged 120

125 130

to enter the grooves of the other member and the action of the parts being such that the vertical walls of the cutting edges will co-operate with each other so that said vertices 5 will have a shearing or cutting action as one passes the other. In other words, the projections 45 and the die-plate 5, on their co-operating surfaces, are provided with diagonal cutting edges, the edges of the respective parts co-operating to have a shearing action. The surface of the projections 45 is formed to represent numerals or other desirable figures and the surface of said figures, etc., is grooved and provided with the 10 cutting edges, as just described. This is clearly shown in Figs. 14 and 15.

I prefer to make the cutters on the die-plate and die-wheel diagonal, because the inclined faces of these cutters have a cam 20 action upon each other and tend to cause relative movement of the plate and wheel, and the diagonal arrangement lessens this tendency. This is because when the teeth come together to punch a check, the effective 25 force tending to give relative movement to the parts in question is exerted horizontally in the direction of the length of the plate, and this effective force is but one component of the force of impact of the wheel upon the 30 plate and is, therefore, much less than this force. The tendency of the plate 6 and die-wheel to get out of position after the die-plate has once been adjusted is, therefore, reduced to a minimum.

35 Mounted on the journal 43^a, at its inner end, is the gear 49, the same being firmly secured to the journal by means of the screw 52, which enters the end of the journal. A holding-plate 50 is secured by means of a 40 screw 51 to the plunger-head, and overlaps the gear 49, so that the latter and shaft carrying the same cannot be displaced when the die-wheel is removed for any purpose. The gear 49 has meshing with it a horizontally-45 arranged pinion 53, which is fixed in any suitable manner to the plunger 38. Thus, the die-wheel is rotated as well as reciprocated through the medium of the handle 33.

The inking mechanism for the die-wheel 50 consists of the lever 54, pivoted at 55 to the plunger-head 42, said lever carrying at its upper end the journal-pin 56, extending toward the front of the machine parallel with the journal 43^a of the die-wheel. The pin 56 carries the inking-roller 57 in position to be constantly in engagement with the executive faces of the die-wheel, said roller being normally held in such engagement by means of the spring 58, secured at one end 55 to the pin 59, projecting from the top of the angular plate 60, secured by means of screws 61 to the top of the plunger-head, and which plate houses the pinion 53. The other end of the spring 58 is secured to 60 the pin 62, projecting from the back of the

lever 54. The lower end of the lever carries the journal-pin 63, parallel with the pin 56 and extending in the same direction, upon which pin is journaled the distributing-wheel 64, arranged in such position as 70 to be normally in contact with the executive faces of the die-wheel. Thus, the inking and distributing rolls properly ink and distribute the latter smoothly and evenly over the executive faces of the die-wheel. 75 The inking and distributing rolls are maintained in position from lateral displacement by means of the face-plate 29 and dial-plate 22.

The feeding mechanism consists of the 80 bar 65, journaled at its opposite, turned ends by means of pins 66, in the lower end of the side frame-portions 15 and at the rear of the machine, said bar being so journaled as to have a vertical rocking movement under control of the vertical bar 67, pivoted at its lower end at 68 to the rear upper corner of the feed-bar 65, and said controlling-bar 67 extending at its upper end through the top-portion 14 of the frame and being 85 provided at said upper end with a bowl 69, for the reception of the finger of the operator, whereby the latter may at will depress the controlling-bar 67 and thus depress the rear side of the feed-bar 65, as 90 shown in Fig. 8. The controlling-bar 67 operates closely against one side of the frame and at its upper end is bent or offset at 70, so as to conform to the shape of the frame and also act as a stop against 95 excess of vertical movement of the controlling-bar. In order to return the controlling-bar to normal position, as shown in Fig. 6, after being depressed, as shown in Fig. 8, a coiled-spring 71 is attached at its 100 lower end to a pin 72, extending laterally from the journal end of the feed-bar at opposite ends of the latter, the upper end of said spring being secured to a pin 73, projecting from the opposite frame-portions 105 15. Thus, the feed-bar is maintained yieldingly in a normal position, which will hold the controlling-bar 67 elevated and the feed-roller 74 normally depressed, as shown in Fig. 6, in co-operative relation with the 110 idle-roll 13, in the base 1 of the frame of the machine. The said feed-roller 74 is journaled at 75 in the feed-bar 65, near one end thereof, and extends toward the front of the machine, the journal of said feed-roller carrying at its rear end a ratchet-wheel 76, secured to said journal by means of the screw 77, a pivotally-mounted pawl 78, under control of spring 79, preventing 115 said ratchet-wheel from having retrograde movement. Feeding movement is imparted to the roll 74, by means of the ratchet-bar 80, mounted for pivotal and reciprocatory action on the screw 81, tapped into the plunger-head 42 at one end thereof, as shown in 120 125 130

detail in Fig. 11, said ratchet-bar being provided with an elongated slot 82, extending longitudinally thereof through which the shank of said screw 81 extends. The 5 ratchet-bar is normally held in yielding engagement with the ratchet-wheel by means of the coiled-spring 83, connected at one end to the pin 84, carried by the ratchet-bar, and at its other end to the pin 85, projecting from the plunger-head. The upper 10 end of the ratchet-bar is provided with a vertically-extending pin 86, which coöperates with an adjusting-lever journaled at 87 to the top of the plunger-head and having its rear end 88 in position to coöperate 15 with the pin 86 of the ratchet-bar 80, the front end 89 of said lever being in position to be manipulated by the operator from the front of the machine after removing the 20 face-plate 29. The position of this adjusting-lever will control the action of the ratchet-bar 80 and determine the number of teeth thereof at its lower end, which will coöperate with the ratchet-wheel 76, and 25 thus control the degree of rotation of the ratchet-wheel and, consequently, the extent of feed of the roller 74. This determines the spacing of the numerals or the disposition of the same when impressed by the die- 30 wheel upon the check or other article. The rack-bar 80 is provided, on its inner face, with a stop-pin 80^a, so positioned as to engage the upper edge of the feed-bar 65, this pin limiting the downward movement of 35 said rack-bar and causing the operation presently described. The positive feed-roller 74 is aided in its work by the idle feed-roller 13 and also by the stripper 90, which coöperates with the die-wheel and 40 die-plate, said stripper being fixed by its shank 91 to the feed-bar 65, substantially midway between the ends of the latter, this stripper being so positioned as to strip the check from, and prevent the same from being 45 lifted by, the die-wheel. The stripper also helps to guide the check and keep it in its proper path of travel through the machine, and in coöperative contact with the gage-bar 19. The stripper is provided with 50 the upturned toe 90^a, to permit the ready entry of the check, and in rear of said toe with the aperture 91^a, through which operate the several faces of the die-wheel. The stripper is made of spring-metal and so 55 formed as to have a yielding action upon the die-plate, or check, under the stress or action of the feed-bar 65, the latter lifting said stripper from the die-plate upon the depression of the controlling bar 67. To 60 still further aid in maintaining the edge of the check against the gage-bar 19, and to prevent said check from slipping toward the front of the machine and away from said gage-bar, I provide a presser-foot, the 65 details of which are shown in Figs. 8 and

10, the same consisting of the forwardly-extending foot-portion 92, carrying the spring-toe 93, having the inclined rib 94. The foot is journaled at 95 in one of the side-walls 15 of the frame at its lower end 70 and at the end of the feed-bar opposite the feed-roller 74. The presser-foot is also provided with the heel-portion 96, having the lower end of a coiled-spring 97, Figs. 5 and 6, secured thereto, the upper end of 75 which spring is connected to the pin 78, to which the spring 71 is connected. The presser-foot is also provided with the vertically-extending arm 98, having the laterally-extending pin 99, under which engages 80 the hook 100, extending from the face of the feed-bar 65. Thus, the feed-bar, when it is rocked as shown in Fig. 8, is caused to lift the presser-foot, as well as the feed-roll 74 and stripper 90, for the purpose of permitting 85 the easy insertion of the check in the machine. The spring-toe 93 is for the purpose of readily yielding under the pressure imposed thereon by the presser-foot spring, and the rib 94 is arranged obliquely with 90 reference to the spring-toe, as shown in Fig. 10, and said toe is arranged at a right-angle to the foot and at a right-angle to the die-plate, for the purpose of creating a constant tendency of the check to move toward 95 and keep in engagement with the gage-bar 19. By the several means just described, the check is properly guided through the machine and compelled to travel in a straight line so that the die-wheel and plate 100 will impress the numerals upon the check in a straight line.

Secured to the inside of the top-portion 14 of the frame and near the front of the machine, and in front of the plunger 38, is an 105 angular plate, the horizontal portion of which is indicated by 101, by which the plate is secured to the top of the frame, screws or pins passing therethrough for the purpose. The depending or vertical portion 102 of the plate extends downwardly to a considerable distance below the periphery of the die-wheel 44 and close to the back of the latter, said portion 102 being provided, at its lower end, with a lug 103, having at 110 its upper end a V-shaped terminal 104, the said lug being in the nature of a pawl adapted to coöperate with the inclined faces of a plurality of pyramidal projections 105, extending from the back of the die-wheel 115 44, see Figs. 7 and 13. The several projections 105 are arranged circularly around and below the periphery of the wheel with their vertices reversed with reference to the vertex 104, of the lug 103; and the projections 105 are spaced apart to just the extent required to permit the lug 103 to pass between each two projections 105. Hence, irrespective of the position of the die-wheel, when the lug 103 engages a face or inclined 120 125 130

surface of one of the projections 105, the die-wheel will be caused to turn on its axis one way or the other according to the projection engaged or which face of said projection is engaged, resulting in compelling the respective die-faces to cooperate accurately with the die-plate 5. This results because the projections 105 are arranged with their bases between a pair of die-
10 faces, or in alternation with the die-faces.

The stop-pin 106 limits the upward movement of the plunger and parts carried thereby by engaging with the top of the plunger-head 42, the cover plate 60, at that end, 15 being cut out at 107 to permit of the co-operation noted. The downward movement of the plunger and parts carried thereby is limited by the fiber or soft washer 37, against which the enlarged lower end 35 of
20 the cap 34 engages.

The numbers or characters 24, on the dial plate 22, correspond with the characters or numbers on the periphery of the die-wheel; and the pointer 27 is set upon the shaft 43 25 of the die-wheel in such manner that, when said pointer is set to indicate any predetermined character or number on the dial-plate, the corresponding number or character on the die-wheel will be set in position to co-
30 operate with the die-plate on the next descent of the plunger. The dial-plate and die-wheel will be numbered or characterized correspondingly; and the dial-plate shown in Fig. 1 corresponds with the die-wheel 35 shown in Figs. 4, 5, 6, 7 and 12 and the development of the periphery thereof shown in Fig. 14. The development of the periphery of the die-wheel shown in Fig. 15 is another form of my invention in this particular, and when used a correspondingly-charactered dial-plate will be applied to the machine.

The ratchet-bar 80, cooperating with the feed-ratchet-wheel 76 has its teeth formed 45 on its inner edge, which converges slightly from the top to bottom, and this ratchet-bar, in its movements with the plunger-head, is caused to slide, relatively to its supporting screw 81, by engagement of the pin 80^a with the feed-bar and the drag of the ratchet-wheel upon said bar. That is to say, the downward movement of the plunger-head carries the pin 80^a into engagement with the feed-bar, which causes the ratchet-bar to move vertically the extent of the slot 82, thus positioning the said bar as a preliminary to its functional action. The spring 83 will cause the ratchet-bar to engage the wheel 76, and the upward movement of the 55 head will first cause the screw 81 to slide in the slot 82, and then engage the upper end of the slot and lift the ratchet-bar to drive the ratchet-wheel. The pin 80^a limits the downward movement of the ratchet-bar.
60 65 The extent of engagement of the ratchet-bar

with the ratchet-wheel is controlled by the adjusting-lever 88-89.

Having thus described the details of my invention, the following mode of operation will be readily understood: It being desired 70 to print and protect the numerals of a given check, the operator first depresses the controlling-bar 67 by the finger at 69, as shown in Fig. 8, resulting in rocking the feed-bar 65 and elevating the feed-roller 74, stripper 75 90, and the presser-foot 99 and its toe 93. The gage-bar 19 will have been previously set in position corresponding to the width of the check or the distance of the space for the numerals from the top edge of the 95 check. The check can now be inserted in the space between the base-plate 1 and the overhanging frame-portions 15 of the machine and will be entered into the machine until its top edge engages the gage-bar 19. The 100 controlling-bar 67 will now be released by lifting the finger from the bowl 69, thus permitting the feed-roller, the stripper, and the spring-toe to engage the top surface of the check at different points. The space 105 where the numerals are to be printed will, of course, be placed directly over the die-plate 5. The die-wheel 44 will now be set by turning the handle 33, which will turn the plunger 38, the pinion 53, gear 49, die-wheel 44 95 and pointer 27, the handle being turned until the pointer is set in register with the first character to be impressed or printed upon the check. The plunger will now be depressed by pressing upon the handle 33, 100 which will depress the die-wheel and bring the desired numeral or character thereon into co-operation with the cutting-face of the die-plate, thus simultaneously printing the desired character and scoring the material of 105 the check throughout the boundary of said character with a plurality of parallel cuts completely through the material of the check. The printing-ink thus becomes completely incorporated in and with the character thus 110 impressed and prevents any possibility of alteration. As the handle is released and the plunger is returned to its upper extreme, the ratchet-bar 80 engages the ratchet-wheel 76 for a limited rotary movement, thus turning the feed-wheel 74 positively, which, in 115 co-operation with the roller 13, will readily feed the check forward the extent desired for spacing the next numeral or character, next to be impressed, from the one last impressed. 120 The rib 94, on the spring-toe 93 of the presser-foot, compels the check, as it is fed forward, to take an inward course tending to crowd the same toward the gage-bar 19, thus causing the successive characters to be impressed in a straight line. The pressure of the spring-toe 93 may be regulated, or the toe may be entirely lifted from co-operation with the check, by means of the short bar 109, carried on the inner end of the pin 110, 130

which extends through the slot 111, at the lower edge of the dial-plate 22, the said bar 109 extending under the spring-toe 93 and sliding horizontally along its length from its rear toward its free end, thus having a lifting action on said toe against its inherent spring tendency to press downwardly. These operations are repeated for every character desired except when a given character is to be repeated, when the step of resetting the pointer 27 may be omitted. When the die-wheel is rotated or turned, the inking-roller and distributing-roller are likewise turned by frictional contact, the 5 inking-roller applying its ink and the other roller equally distributing the ink over the die characters. When a character is to be repeated in succession, the same operation may be repeated so as to ink the character as 10 a preliminary to each imprint. Thus, the characters impressed will be uniform in appearance and too much ink will not be applied, and one will not appear lighter than others. If the die-wheel is turned carelessly, 15 or if, by any chance, the same should not be set so that the desired character is squarely over the die-plate 5, the die-wheel will, as the plunger is depressed, be turned in either direction, as may be required, the additional 20 amount necessary to place the required numeral directly over the die-plate 5 for proper and accurate coöperation between the two, this being brought about as before stated by the engagement of the vertex 104, of the 25 lug 103, with one or the other of the faces of that lug 105 which happens to traverse the path occupied by said lug.

From the foregoing it will be clear that, 30 when the parts of the machine are once adjusted or set for proper operation, no changes or adjustments are necessary except such as may be required to regulate the feed and bring into action the various parts of the die-wheel, as above described. Hence, 35 the machine cannot readily get out of order or be put out of order, and as the parts are compactly arranged, the movements are short, and the parts are very strong, the machine is necessarily strong and durable.

40 When a new inking-roll is required, the face-plate 29 can be quickly removed by removing the screws 30 and 31. The inking-roller can then be quickly slipped from its journal-pin and a new roller applied to the latter.

45 The face-plate keeps the inking-roller on its journal-pin. A new distributing-roller is seldom required. The removal of the face-plate 29 also permits adjustment of the feed-regulator 88-89, the latter being just below the upper edge of the dial-plate when the plunger-head is in its upper position. The stop-pin 106, which limits the upward movement of the plunger, prevents the inking-roller from impinging against the inner side 50 of the frame and the latter is preferably hol-

lowed out as at 107 and 107^a to accommodate the rolls 57 and 64 during any movement the lever 54 may have, as when an inking-roller is removed or applied. In Figs. 6 and 12, the material of a check, for example, 70 is indicated at 108, and in the latter figure the manner in which the coöperating knife edges, of the dial-plate and die-projections, score or cut through the material of the check, can be readily seen.

Having thus described my invention, what I claim and desire to secure by Letters Patent is:

1. A check printing machine comprising a frame member having a base; a second frame member carried by, and overhanging, the base member; scoring and printing means carried by the frame members; means whereby said scoring and printing means are caused to operate upon the work; a gage-bar frictionally held between, and slidable relatively to, said frame members and extending from side to side of said members within the machine; and means carried by said gage-bar whereby the same may be manipulated from the outside of the machine.
2. A check printing machine comprising a casing; means inclosed by said casing for marking a check; said casing having a check-guiding slot one part of which is at an angle to the other; an adjustable gage-bar extending across one portion of said slot from side to side of the machine; and means carried by said gage-bar at its opposite ends outside of the casing for manipulating said bar within said slot to regulate the width of the latter to accommodate the varying widths of checks.
3. A check printing machine comprising a frame member having a base; a second frame member carried by, and overhanging, the base; scoring and printing means carried by the frame members; means whereby said scoring and printing means are caused to operate upon the work; the two frame members being spaced apart to form guideways at an angle to each other; a gage-bar frictionally held in said guideway and extending entirely across the same from side to side of the machine; and means whereby the gage-bar may be manipulated from the outside of the machine.
4. A check protector having, in combination, a frame composed of two separable members having a check-guiding slot between them; check scoring and printing means mounted to operate within the frame; a gage-bar extending across the frame from side to side between the two frame members within said slot; feeding means within the frame arranged to advance the check parallel with the gage-bar; and means for manipulating the gage-bar from the outside of the machine.

5. A check protector having an inclosing frame and, in combination therewith, a plunger, and means for mounting the plunger in the frame whereby the same may have rotary and also right-line reciprocatory movements; a die-wheel having die characters extending parallel with its axis and said wheel being carried by said plunger with its axis at an angle to the latter; means coöoperating with the die-wheel for scoring the check; means for inking the characters of the die-wheel; means for feeding the check immediately after each impression made by the die-wheel; and means acting upon the check for positively guiding the same through the machine.
6. A check protector having an inclosing frame; a plunger mounted in said frame so as to have rotary and also right-line reciprocatory movements; a die-wheel journaled to operate with said plunger, said wheel having a plurality of peripheral characters arranged parallel with the axis of said wheel; means coöoperating with the characters of said wheel for scoring the check; means for inking the characters; means for feeding the check immediately after each impression made by the characters; and means for positively guiding the check through the protector.
7. A check protector comprising a frame having a base-member and an overhanging member forming between them a space through which the check may be guided; a rotary die-wheel mounted in the front of the overhanging member; a coöperating die-plate carried by the base-member; a member in which the die-wheel is carried, mounted in said overhanging member and confined to vertical reciprocations therein to move the wheel toward and from the die-plate; a feeding mechanism having a feed-member arranged in coöperative relation to the die-wheel in rear thereof; and means located in the space between the two frame-members and in rear of the feed-member for guiding a check through the machine.
8. A check protector comprising a frame having a base-member and an overhanging member forming between them a space through which the check may be guided; a member mounted in the overhanging member so as to be reciprocated therein; a rotary die-wheel mounted in said last-named member and arranged at the front of the overhanging member; a coöperating die-plate carried by the base-member; feeding mechanism having a feed-member arranged in coöperative relation to the die-wheel in rear thereof; means located in the space between the two frame-members and in rear of the feed-member for guiding a check through the machine; and means for engaging the check in front of the feed-member and coöperating with the rear guiding means to advance the check in a straight course through the machine.
9. A check protector comprising a frame having two separable parts combined so as to provide a check-guiding slot or space between them; check-scoring means arranged in coöperative relation at the front of the frame; feeding mechanism having a feed-member arranged in rear of the check-scoring means; guiding means for the check extending across the frame within the same and in rear of the feeding member; and additional check-guiding means arranged in front of the feeding means and operating to keep the check in engagement with the first-named guiding means.
10. In a check protector, the combination of a casing for receiving a check to be marked; means in the casing for marking the check; a feeding-member normally in position to engage the top of and feed a check; coöperating yielding means for normally engaging the top of and controlling the check; and a controller coöperating with said yielding means and extending outside the machine for lifting the yielding means from the check.
11. In a check protector, the combination of a casing for receiving a check to be marked; means in the casing for marking the check; feeding means having a feed-member normally in position to engage the top of and feed a check; a presser-foot for normally engaging the top of and controlling the check; and a controller coöperating with the said feed-member and said presser foot, and extending outside of the machine for lifting said feed-member and foot from the check.
12. In a check protector, the combination of a casing for receiving a check to be marked; means in the casing for marking the check; feeding means having a feed-member normally in position to engage the top of and feed a check; a presser-foot for normally engaging the top of and controlling the check; a stripper coöperating with the check-marking means and arranged to normally engage the check; and a controller coöperating with the said feed-member, presser-foot and stripper for lifting the same from the check.
13. A check protector comprising a frame having a face-member and an overhanging member associated so as to provide a space between the two through which a check may be passed; a plunger mounted in the overhanging member; a head confined to right-line reciprocations in said latter member; connections between the head and plunger enabling the latter to be rotated; a rotary die-wheel having a plurality of separated executive faces journaled in the head; a die-plate mounted in the frame for coöperation with the executive faces of the die-wheel; 130

- means connecting the plunger and die-wheel for rotating the latter so as to move the said faces to effective position; and means for insuring the accurate engagement of the executive faces of the die-wheel with the plate.
14. A check protector comprising a frame having a face-member and an overhanging member associated so as to provide a space between the two through which a check may be passed; a plunger mounted in the overhanging member; a head confined to right-line reciprocations in said latter member; connections between the head and plunger enabling the latter to be rotated; a rotary die-wheel journaled in the head and having a plurality of separated executive faces arranged in parallelism with the axis of the wheel; a die-plate mounted in the frame for co-operation with the executive faces of the die-wheel; means connecting the plunger and die-wheel for rotating the latter so as to move the said faces to effective position; and means for insuring the accurate engagement of the executive faces of the die-wheel with the plate.
15. A check protector having, in combination, means for simultaneously scoring and printing the check; means for feeding the check through the machine; and means for maintaining the check in a straight line while being fed, including means for engaging the edge of the check; and means for operating upon the check tending to move it toward the edge-guiding means.
16. A check protector having, in combination, means for simultaneously scoring and printing the check; means for feeding the check through the machine, including a rotary member; and means for maintaining the check in a straight line while being fed, including edge-guiding means and surface-engaging means, the action of which latter is to tend to force the check toward the edge-guiding and feeding means.
17. A check protector comprising means for marking a check; means for feeding a check through the protector, and a presser-foot mechanism for controlling the action of the check; the latter mechanism including a resilient toe for co-operating with the check; and means whereby the toe may be lifted from the check without lifting or disturbing the presser-foot mechanism.
18. A check protector comprising means for scoring a check; means for feeding the check through the machine; means for pressing upon the check to maintain it in proper line in the machine, said means tending to move the check inwardly; and means for stripping the check from the check-scoring means.
19. The combination of a casing; means in said casing for marking a check; said casing having an opening for admitting the check; a toe having an oblique rib for engaging the check and tending to draw the same into the casing when the check is moved to be marked in several places in succession.
20. A check protector comprising means for marking a check; means for feeding the check to bring the successive portions thereof into position to be marked; a stripping device; a presser-foot; and means for manually actuating the feeding means, the stripping device and the presser-foot, said parts being connected to the actuating means so that the feeding means and the stripping device can first be lifted and then the presser-foot lifted from the check.
21. A check protector comprising means for marking a check; means for feeding the check to bring the successive portions thereof into position to be marked; a stripping device; and means for manually actuating the feeding means and the stripping device, said parts being connected to the actuating means so that the feeding means and the stripping device can be lifted from the check.
22. In a check protector, the combination of a casing having means therein for marking a check; a feed-bar in the casing; means for feeding the check; a presser-foot and a stripper plate carried by the feed-bar; and means for actuating said feed-bar to separate the feeding means, the presser-foot and the stripper plate from the check.
23. A casing comprising an angle-piece forming the bottom and back, and an inverted U-shaped piece forming the top and sides, said casing having spaces between said angle-piece and said U-shaped piece to provide a passage through the casing from side to side thereof, and means for marking a check in said casing as it is passed through said passage.
24. A casing for a check protector comprising an angle-piece forming the bottom and back, an inverted U-shaped piece forming the top and sides and secured to the top of the back so as to cause the U-shaped piece to overhang the base, said casing having spaces between said angle-piece and said U-shaped piece to provide a passage through which a check may be passed from side to side of the frame, substantially as described.
25. A check protector comprising a casing, and means inclosed by said casing for marking a check, said casing having a space for admitting said check, and an adjustable bar extending through said space from side to side thereof and having manipulating means at its opposite ends outside the casing for varying the extent of said space.
26. A check protector comprising a casing and means in said casing for marking a check, said casing having a space extending into the same in one direction and then extending in another direction to admit the check.

check to be marked, whereby a check of greater extent than one of the dimensions of the casing can be received by the casing, and means for varying the length of said space.

27. A check protector having a frame provided with a base and solid back; dialed face and solid ends or sides; the face and sides being associated with the back so as

10 to overhang the base and provide an L-shaped slot between them through which the check may be guided; and a gage bar frictionally held in said slot and having means on the outside of the frame for manipulating the same to adjust the slot for varying widths of checks.

28. In a check protector, the combination of a die-wheel and a die-plate, said wheel and plate having coöperative cutting edges 20 extending diagonally of the axis thereof; means for rotating the wheel and reciprocating it in a right-line relatively to the die-plate; and means for relatively adjusting said wheel and plate in the direction of the axis of the wheel so as to enable the cutting edges to be set in proper coöperative position.

29. In a check protector, the combination of a rectangular casing having guide-ways

in opposite sides, a plunger having a head 30 the ends of which coöperate with said guide-ways, a die-wheel carried by the plunger head, a feed wheel mounted in said casing below the plunger head, feeding means co-operating with the feed wheel, and means 35 carried by the plunger head for actuating said feeding means.

30. A check protector comprising a scoring mechanism for marking a check; inking mechanism coöperating with the scoring 40 mechanism whereby the latter may also ink the scored part of the check; feeding means for advancing the check to the scoring means; multiple means operating upon the edge and surface of the check for properly 45 guiding the check to the scoring means under control of the feeding means; and means for shifting a part of the scoring means whereby the characters may be brought to the printing position. 50

In testimony whereof I have hereunto signed my name in the presence of two subscribing witnesses.
